(57) **CLAIM**

(21) Appl. No.: **29/334,383**

The ornamental design for a hearing aid with receiver in the ear, as shown and described.

(22) Filed: **Mar. 25, 2009**

DESCRIPTION

(30) **Foreign Application Priority Data**

Sep. 26, 2008 (EM) 001010250-0001

FIG. 1 is a perspective view of a behind-the-ear (“BTE”) component and a front perspective view of an in-ear component of the hearing aid;

(51) **LOC (9) Cl.** **24-99**

FIG. 2 is a front view of the BTE component and a side view of the in-ear component of the hearing aid;

(52) **U.S. Cl.** **D24/174**

FIG. 3 is a side view of the BTE component and a rear perspective view of the in-ear component of the hearing aid;
FIG. 4 is a rear view of the BTE component and a side view of the in-ear component of the hearing aid;

(58) **Field of Classification Search** D24/173–175,

FIG. 5 is a side view of the BTE component and a front perspective of the in-ear component of the hearing aid;

D24/182, 106; D14/205, 223, 224, 249;

FIG. 6 is a bottom view of the BTE component and a top view of the in-ear component of the hearing aid; and,

381/23.1, 312, 322–324, 328–330, 334, 381;

FIG. 7 is a top view of the BTE component and a bottom perspective view of the in-ear component of the hearing aid.

181/129, 137
